SEPARATING MEANS FOR SHEET-FEEDING MACHINES.

1,174,391.

Specification of Letters Patent. Patented Mar. 7, 1916.

Application filed February 10, 1913, Serial No. 747,378. Renewed July 28, 1915. Serial No. 42,453.

To all whom it may concern:

Be it known that I, ERNEST O. CARTWRIGHT, residing at Springfield, in the county of Clark and State of Ohio, have 5 invented certain new and useful Improvements in Separating Means for Sheet-Feeding Machines, of which the following is a specification.

My present invention relates to that class 10 of separating mechanisms employed to effect the separation of the top sheet from a pile of paper or similar material and advance it to a position to be operated upon by a printing press.

15 My present invention, while adapted for use in connection with any of the types of printing machines having conveyer mechanisms that take up the separated sheet or sheets and present the same to the printing elements of the printing press, is more especially applicable for use in connection with my new and improved automatic printing press disclosed in my copending application, Serial No. 747,375 filed on even date 20 with this application, since it forms, as it were, a coöperative part of the complete automatic press mechanism shown and described in the said copending application.

The primary object of this invention is 30 to provide a simple and economical construction of parts having such connected relation whereby to encompass the same in a relatively small space, and to afford a greater degree of reliability in the separation 35 of a single sheet from the top of the pile than is now apparent in separators of the same general class to which my present invention belongs.

Another object of my invention is to provide 40 certain improvements in which are included timing devices that are applied to the sheet separating and forwarding means whereby to provide for the easy adjustment of the separator to various sizes and qualities 45 of paper and other material.

With other objects in view, that will hereinafter appear, my invention comprehends a mechanism for the purposes stated that embodies the peculiar arrangement 50 and novel combination of parts hereinafter set forth, specifically pointed out in the appended claims and illustrated in the drawings hereunto annexed, in which—

Figure 1 is a side elevation of my paper

separating mechanism, so much of my complete printing machine being shown to clearly locate the said mechanism, the top separating rolls being in their "up" position. Fig. 2 is a top plan view thereof, parts being broken away. Fig. 3 is a vertical cross section thereof, on the line 3—3 on Fig. 1. Fig. 4 is a detail cross section on the line 4—4 on Fig. 3. Fig. 5 is a similar view on the line 5—5 on Fig. 3. Fig. 6 is a side elevation similar to Fig. 1 65 with the top separator rolls shown at their "down" or sheet forwarding positions. Fig. 7 is a top plan view of the parts shown in Fig. 6 portions being broken away. Fig. 8 is a cross section on the line 8—8 on Fig. 6. Fig. 9 is a detail perspective view of the movable clutch member carried on the lower separating roll shaft, by which rotary motion is imparted to the said shaft, at times. Fig. 10 is a detail perspective 75 view of the fixedly mounted clutch member on the lower separating roll shaft. Fig. 11 is an enlarged detail sectional perspective view of the two part separator cam hereinafter specifically referred to. Fig. 12 80 is a cross section on the line 12—12 on Fig. 7 looking in the direction of the arrow, the parts being positioned as shown in Figs. 1 and 2. Fig. 13 is a detail plan view that illustrates the adjustable sheet supporting 85 fingers. Fig. 14 is a detail perspective view of one of the said supporting fingers. Fig. 15 is a detail perspective view of the upper and lower separating rolls. Fig. 16 is a detail perspective view of one of the 90 "initiators" or paper feeding wipers. Figs. 17—18—19 and 20 are a series of diagrammatic views that illustrate the positioning of the upper and lower separating rolls in 95 relation to the governing cam on the main separator shaft and also the various positions assumed by the "initiator" in relation to the aforesaid devices.

In my separating means I have particularly provided a compact arrangement of 100 the parts and for affording a maximum degree of reliability in the separating of a single sheet from the top of the pile and for the utilization of certain timing devices that coöperate with the said separating 105 means and the forwarding mechanism that receives the separated sheet, and arranged for synchronous action with the printing

means, it being also adapted for easy adjustment for working various sizes and qualities of paper and other material.

Referring now more particularly to Fig. 1 of the drawing, 1 designates a revolving shaft that extends transversely over the top of the pile of sheets to be separated, and it carries a plurality of members 2 hereinafter termed initiators, since they initiate the separating of the top sheet from the pile, and deliver it to the main separating members, in the nature of two (or more) sets of coacting rolls located in advance of the top of the pile, and in position to receive between them, the top sheet or sheets advanced from the pile by the initiators 2.

The initiators each comprise a lever-like arm 3 adjustable circumferentially on shaft 1 and laterally adjustable thereon by a set screw connection 4 see Fig. 7. The arms 3, shown in detail Fig. 16, include a spring controlled member 5 that carries a strip 6 of frictional material, preferably rubber, and is pivoted on the pendent arm 3 whereby to provide for a yielding movement of the member 5 under adjusted spring tension, to thereby effect a resilient contact between the initiators and the top of the sheet pile, the members 6 acting to wipe off the top sheet from the pile of sheets as the said initiators, at predetermined times, are swung around with the shaft. Shaft 1 is journaled in a rocker frame 7, consisting of a pair of opposite side arms that are fulcrumed on a shaft 8 journaled in the side frames of the separator and acts as a supporting pivot for the said rocker frame 7. The shaft 8 is driven by a gear 9 on the main driving shaft 10 of the separator, meshing with a gear 11 on one end of the said shaft 8, which on its other end, carries gears 12-13 the latter of which is engaged by a large gear 14 on the shaft 1. In this manner a constant rotation of shaft 1 is effected.

15 designates a shaft whose opposite ends are journaled in the side arms of the rocker frame 7, and the said shaft 15 carries the upper separating rolls 16, and is driven by a gear 17 that meshes with the small diameter gear 13 on the shaft 8 that also meshes with and drives the large gear 14.

18 designates a shaft located below and in vertical alinement with the shaft 15 and it carries the lower separating rolls 19 that coöperate with the upper rolls 16 in the manner and for the purpose presently explained. The shaft 18 is journaled in the side frame 20 of the separating mechanism and at one end, outside the frame, it has a clutch 21 for intermittent rotation in a determined direction. Clutch 21 includes a flanged sleeve 22 having projections 23, that serve as one member of the clutch, and loosely mounted to rotate on the sleeve 22 and

lengthwise slidable thereon is a pinion 24 that meshes with the largest pitch diameter 12 of the double gear on the shaft 8. Pinion 24 includes a grooved hub with projections 25 on its face that serve as the other member of the clutch and for coacting with the opposing projections 23. The groove in the hub 24 forms a raceway for one prong of a controlling yoke 26 that is rockably mounted and has a forked portion for straddling the said grooved hub. One prong of the yoke contacts with an angle boss 27 see Figs. 2, 3 and 8 mounted on a cross brace rod 28 on the rocker frame 7. Yoke 26 is normally pressed outwardly to release the clutch members 25 and 23, by means of the spring 29.

The main driving shaft 10 carries a large gear 9 that meshes with and drives a smaller gear 11, on the shaft 8 and with a sprocket or other suitable connection for receiving power from the printing mechanism. Shaft 10 on that end opposite the end that has the gear 9, carries a cam device consisting of an inner disk 32, and an outer disk 33, the inner disk being formed with a relatively long hub and the other 33, with a shorter hub, the long hub having a set screw connection for adjusting it on the shaft 10 and the other hub a similar set screw for adjusting it on the hub of the disk 32. A portion of the circumference of each of the disks 32-33 is cut away to a smaller desired diameter. By using two disks and cooperatively adjusting them as stated, makes it possible to alter the circumference of both pitches of the cam, and the adjustment relative to the shaft 10 affords the proper timing under different conditions that might confront the separating mechanism. The brace rod 28, on the rocker frame, carries a roller 34 that travels over the face of both cam disks.

To provide for a proper action of my separating mechanism, particularly the upper rolls 16, the pile of sheets is kept in perpendicular alinement with the wiping or receiving surface of the said separating rolls, by means of a plate 35 pivotally suspended in the machine framing, best shown in Fig. 12, by reference to which it will be noticed, along the top of the said plate 35 are a series of rodlike uprights 36, that have stud pintles for rotatably engaging sockets in the said plate 35. The upper ends of the rods 36 have flexible extensions, and these are bent to a proper radius to act as fenders 37 whose function is to keep the edge of the sheets from contact with the lower separating roll, and at the same time serve as supports for the sheets when pushed between the rolls for separation. Since the rods 36 are laterally shiftable, their fender portions may be adjusted to different locations along the edge of the sheet pile, or

with a view of overcoming buckling in the sheet, as it passes from the separating rolls onto the conveyer devices. The separating rolls are each surfaced with some substance 5 of great frictional quality, preferably rubber.

The forwardly feeding set of rolls 16, being the upper set in my present showing, are surfaced with a very soft clinging rubber and located above the line in a plane 10 of the top of the paper pile, and the said rolls 16 are continuously rotated, at a predetermined speed, in the forward direction, so that the sheet or sheets pushed beneath it, by the initiators or feeders, will be wiped 15 or drawn from the pile.

The upper rolls 16 as before stated, are carried by a rocking frame and are lifted, at proper times, by the cam devices heretofore explained. The other or lower set of 20 rolls 19 are surfaced with a substance of less frictional quality than that of the other rolls and the said lower rolls 19 are located immediately below the top set of rolls in such a manner that the top surface of 25 the said rolls is in a horizontal line with the top of the sheet pile. The lower set of separating rolls 19 is intermittently rotated at a speed somewhat greater than the top rolls, and in the direction that the sheet or 30 sheets pushed above it by the initiators are driven back upon the pile, see Fig. 19. The aforesaid set of rolls 19 is secured by any suitable means against rotation in the (opposite) forward direction, and to accomplish 35 this purpose the clutch member 21 is engaged by a friction segment 30 swivelly connected with an adjusting screw 31 stationed in the standard 38 which in turn is secured to the frame 20. The intermittent 40 rotations of the said rolls 19 is effected by the rise and fall of the top rolls 16 with the rocker frame that carries the brace or cross rod 28, on which is mounted a beveled clutch shifter 27 that engages the yoke 26 45 and moves it against the tension of its spring 29 and in consequence connects the two clutch members, hereinbefore referred to, and thereby puts into action the drive for rotating the lower set of rolls 19 when 50 the top rolls are in contact with them or with the sheet or sheets between the two sets of rolls, (see Fig. 8).

In the practical embodiment of the sheet separating means described I have found, 55 on account of the different frictional surfaces of the opposing rolls, that the frictional contact between the top rolls and the sheet or sheets beneath it, is greater than the friction of the bottom rolls against the sheet between the rolls, and the friction between the bottom rolls and a sheet in contact therewith is greater than the friction between that sheet and the one in contact with it and between the rolls. By reason 60 of the arrangement of the separating rolls

and their coöperating actuating means, the practical operation of the said rolls is as follows;

Referring now to Fig. 17, which shows the wiping member or strip 6 of the "initiator" devices, just about to engage the top of the pile of sheets, and it should be stated that in the practical application of my sheet separating means to my complete printing press disclosed in my copending application No. 747,375 and before referred to, the caliper rod 39 which forms a specific part of the sheet pile elevating means, also shown in the said copending application and in another copending application filed by me, Serial No. 747,379, rises from the pile of sheets and frees the top sheets.

As the member 6, travels forwardly, as indicated by the arrow 43, the upper ones 85 of the sheets are projected forward, the number of sheets thus advanced depending on the frictional quality of the paper, it being understood, since the lower rolls 19 at this time, are stationary, they do not 90 retard the initial advancement of the top sheets as stated and to the position indicated on Fig. 18, at which time the initiatory feed action on the paper sheets is about completed.

When the parts are positioned as seen in Fig. 18, further forward movement of the cam disks, see arrow 40, releases the roller 34, and the frame 7 that carries the upper rolls 16 is caused to assume the position 100 shown in Fig. 19.

To prevent a possible drag of the wiper member 6 after it has completed its sheet forwarding function, the frame 7 is caused to instantly lift, when the timing cam reaches the position in Fig. 18, that is to say, that end that carries the wiper member 6 is quickly swung upwardly and for such purpose a thrust spring device 41 is used which is arranged in a manner that is 110 clearly understood by referring to Fig. 12 of the drawing. To further provide for moving or causing the wiper member 6 to "kick back" and be positively free from engagement with the sheets the pivotally hung 115 and pendent arm 3 of the initiators or wipers each engage an upwardly extended member 50 that is apertured to allow for a limited movement of the said member 50 along a rod 51 upon which is mounted a 120 coiled spring 52, (see Figs. 12 and 16) the said spring 52 being so arranged that when the wiper 6 engages the sheets, as in Fig. 18, the said spring 52 will be slightly compressed and then be under sufficient tension 125 to cause the wiper member to instantly "kick back" to its straightened position (see Fig. 19) when the timing cam that engages the end of the frame 7 is down.

It should be here stated that while the 130

frame 7 under ordinary conditions will drop to the position shown in Fig. 19 by gravity, practical experience has demonstrated the employment of spring pressure for quickly lifting the outer end of the frame 7 and holding its other end down on the timer cam.

As the above operation takes place the lower feed rolls 19 are brought into gear 10 with the top rolls' driving means through clutch devices 25 and 23, and caused to rotate in a direction reverse to the advancing movement of the sheets, see arrow 42, Fig. 19. The top rolls now forward the top sheet 15 only in the direction of its travel, since the bottom rolls now act successively upon the under sheets as each is exposed to their surfaces, and not only retard the forward slide of the said under sheets but return them in 20 the direction of the travel of the bottom rolls and reverse to the feed movement of the uppermost sheet. Furthermore, the greater speed of the bottom rolls takes care of any varying number of sheets in order 25 that all, except the top one, are sent back onto the pile before the initiators make their subsequent impulse.

When my sheet separating means is included in my automatic press, as before 30 noted, the primary driving means that controls the entire mechanism of my automatic press, moves continuously and the timing devices that coat therewith are such, that the sheet separators are taken care of, not 35 alone for a delivery of a sheet to the printing cylinder at the proper time, but also for a correct synchronous action with the elevator from which the sheets are taken and the conveying mechanism that form a 40 part of my complete automatic high speed printing press.

Briefly stated the operation of my sheet feeding and separating means is as follows: 45 the parts now being as shown in Fig. 17. The "initiators" start any number of sheets from the top of the pile of sheets; the top rolls are lifted, the bottom rolls now being 50 stationary. At the proper time the lowering of the top rolls into contact with advanced sheets starts the bottom rolls in their revolution, as the top rolls are now advancing the top sheet toward its destination, while the bottom rolls, with greater speed are 55 returning the under sheets to the top of the pile. At a predetermined moment, according to the physical condition of the material fed, the top rolls are lifted, the rotation of the bottom rolls thereby stopped, the mechanism referred to now awaiting the action 60 of the initiators for the subsequent operation. If only one sheet should be advanced and presented to the rolls 16 and 19 by the initiators, the frictional advantage of the top rolls 16 insures the advance of the sheet, 65 while the bottom rolls 19 have nothing to do.

From the foregoing description taken in connection with the drawings, it is believed the complete construction of my present invention, its operation and advantages will be readily apparent to those skilled in the art to which it relates.

What I claim is:

1. In a sheet feeding and separating mechanism in which are included opposing surfaces for engaging sheets advanced from a pile of sheets; a means for advancing the topmost sheet from the pile toward the said opposing surfaces, the said means including a rotatable body having a surface for frictionally engaging the topmost paper sheet and advancing it in the direction of rotation of the said body, means for instantly lifting the said surface that engages the sheet when the latter reaches its predetermined limit of sheet advancing movement, the said means including devices for bodily lifting the contacting rotatable body and other means carried by the said rotatable body for imparting a vertical swinging movement to the said surface that engages the topmost sheet as the said surface is lifted with the rotatable body.

2. In a sheet feeding machine in which are included opposing surfaces that engage sheets advanced from a pile of sheets, a means for advancing the topmost sheet from a pile of sheets to be engaged by the said opposing surfaces, the said means including a rockably mounted frame, an arm that is rotatably mounted on the said frame, a member pivotally connected to the said arm and which has a surface for frictionally engaging and advancing the topmost sheet of a pile of sheets, means for holding the rockable frame under tension as the said member engages and advances the sheet and adapted for instantly swinging up the said frame and the sheet engaging member when the top sheet is advanced to a predetermined point, the said paper engaging member being mounted on the rotatable arm, and devices carried by the said arm that operate with the said member for imparting an upwardly swinging movement to said member as it is lifted from the paper when the rockable frame is swung up.

3. A sheet separating means for sheet feeding means that advance the sheets from the top of a pile of sheets continuously maintained at a predetermined plane; the said separating means comprising a pair of superimposed rolls, the upper of which has a relatively soft frictional surface, the lower one of which has a relatively hard frictional surface, the upper roll having vertical movement with respect to the other roll, means for intermittently advancing at least one of the sheets from the pile onto the lower roll, other means for bringing the top roll down against the sheet and the lower roll after the

sheet has been initially advanced, said other means including a driver for rotating the top and bottom rolls, the top roll forwardly and the bottom roll rearwardly and at 5 greater speed than the top roll.

4. A sheet separating means for sheet feeding means that advance the sheets from the top of a pile of sheets continuously maintained at a predetermined plane; the 10 said separating means comprising a pair of superimposed rolls, the upper of which has a relatively soft frictional surface, the lower one of which has a relatively hard frictional surface, the upper roll having vertical movement with respect to the other roll, means for intermittently advancing at least one of the sheets from the pile onto the lower roll, other means for bringing the top roll down against the sheet and the lower roll after the 15 sheet has been initially advanced, said other means including a driver for rotating the top and bottom rolls, the top roll forwardly and the bottom roll rearwardly and at greater speed than the top roll, and further 20 means for throwing the sheet advancing means out of its sheet advancing action immediately after the separating rolls engage the sheet or sheets.

5. In a sheet feeding and separating 30 mechanism for advancing sheets from a pile of sheets, the combination with an automatically lifted sheet pile elevator, and a continuously movable sheet conveyer; of means for feeding the topmost sheet or sheets from 35 the pile, other means for engaging the sheets as they are primarily advanced from the pile and which delivers the topmost sheet to the sheet conveyer, the said means comprising top and bottom opposing rolls, timing devices that lift the top roll from the bottom roll at predetermined times to thereby arrest the movement of the bottom roll and for cutting out the means that advance the sheet from the pile while the opposing 40 rolls are in active engagement with the primarily advanced sheet.

6. In a sheet feeding and separating mechanism adapted for advancing sheets from

a sheet pile to a sheet conveyer that carries the sheet to a printing mechanism; a plurality of continuously rotated rolls normally out of operative position, another plurality of separating rolls normally in a fixed position relatively to the pile of sheets, means for intermittently bringing the continuously 50 rotated rolls into contact with the other rolls and simultaneously imparting rotation to the said other rolls at a greater speed than the continuously rotating rolls.

7. In a sheet feeding and separating mechanism adapted for advancing sheets from a sheet pile to a sheet conveyer that carries the sheet to a printing mechanism; a plurality of continuously rotated rolls normally out of operative position, another plurality of separating rolls normally in a fixed position relatively to the pile of sheets, means for intermittently bringing the continuously rotated rolls into contact with the other rolls and simultaneously imparting rotation to the 55 said other rolls at a greater speed than the continuously rotating rolls, and means for securing the intermittently rotated rolls against rotation in a direction opposite to their normal direction of rotation. 75

8. In a sheet feeding and separating mechanism adapted for advancing sheets from a sheet pile to a sheet conveyer that carries the sheet to a printing mechanism; a plurality of continuously rotated rolls normally out of operative position, another plurality of separating rolls normally in a fixed position relatively to the pile of sheets, means for intermittently bringing the continuously rotated rolls into contact with the other rolls and simultaneously imparting rotation to the other rolls at a greater speed than the continuously rotating rolls, the said continuously rotating rolls having a 80 surface of greater frictional efficiency than the opposing surface of the intermittently rotated rolls. 85
